(57) **CLAIM**

The ornamental design for a shoe with sole having transparent windows and internal spheres, as shown and described.

DESCRIPTION

FIG. 1 is a bottom view of a shoe with sole having transparent windows and internal spheres showing my new design;

FIG. 2 is a bottom view thereof, with transparent shading removed for clarity purposes;

FIG. 3 is a cross section taken through line 3-3 of FIG. 2; and,

FIG. 4 is a cross section taken through line 4-4 of FIG. 2. The broken lines showing of the internal and lower portions of the spheres in the cross section views represent features which form no part of the claimed design. The broken lines adjacent to the transparent window and the spheres shown in the cross section views represent boundary lines which form no part of the claimed design. The broken lines immediately adjacent to the shaded areas define the bounds of the claimed design and form no part thereof. The broken lines showing the remainder of the shoe are for environmental purposes only and form no part of the claimed design.
